UNITED STATES PATENT OFFICE.

PERCY R. MOFFITT, OF PAWTUCKET, RHODE ISLAND.

KEY-LOCKING ESCUTCHEON.

1,405,144.

Specification of Letters Patent. Patented Jan. 31, 1922.

Application filed May 31, 1921. Serial No. 473,852.

To all whom it may concern:

Be it known that I, PERCY R. MOFFITT, a citizen of the United States, residing at Pawtucket, in the county of Providence and State 5 of Rhode Island, have invented new and useful Improvements in a Key-Locking Escutcheon, of which the following is a specification.

This invention relates to certain new and 10 useful improvements in a key locking escutcheon, and it has for its primary object to provide an escutcheon embodying means for preventing the rotation or turning of the key after having been disposed within the 15 lock and actuated to render the latter operative.

The invention further resides in an improved escutcheon having means for preventing the withdrawal of the key as well as 20 preventing rotation of the key to function properly.

In the drawing,

Figure 1 is a vertical section through the 25 improved escutcheon depicting the key-locking device in its operative position and showing the door and its lock by dotted lines;

Figure 2 is a front elevation thereof taken about on line 2—2 of Figure 1;

Figure 3 is a perspective view of the 30 escutcheon per se; and

Figure 4 is a similar view of the slide element.

Referring more in detail to the drawing, the 35 numeral 1 indicates the door having the usual lock 2 and key openings 3 leading through the wood on opposite sides thereof to the outside escutcheon 4 and the inside escutcheon, the latter constituting and embodying the subject matter of the present invention.

The improved escutcheon consists of a 40 plate 5 having the key opening 6 and a transversely intersecting groove 7 of dovetailed section, the latter being designed to receive the slide 8 of corresponding cross section. The slide is provided intermediate its ends with a screw threaded aperture 9 to receive a locking screw 10, the same having a knurled outer end and a smooth tapering inner 45 end 11.

In operation, the key 12 is inserted through the escutcheon plate 5 into the lock 2 and then turned to throw the lock bolt to secure the door. The key is then turned suf-

ficiently to be engaged by the locking screw 55 and be held against turning in such direction as to unlock the door, i. e. the key is rotated for one complete turn to throw the bolt of the lock, and then reversed to unlock the door, and in these locks the key will be 60 turned but slightly more than a complete revolution before the locking screw is threaded inwardly to bring its point 11 into the path of the bolt-throwing part of the key.

Obviously, if it is desired to prevent throwing of the bolt to secure the door, the locking screw may be set on the opposite side of the bolt-throwing part of the key. It will be apparent that a simple device has been provided which will not only hold the key 70 firmly against unauthorized actuation but also prevent dislodgment of the same by some one from the outside the slide performing this latter function. The device is simple in construction and can be expeditiously 75 manufactured at but little cost so that it can replace the ordinary escutcheon with but slightly additional expense. The opening 3 between the plate 5 and the lock 2 provides a chamber into which the screw is withdrawn 80 when it is desired to actuate the key under normal conditions. It is therefore unnecessary to remove the slide except to remove the key when the screw is first displaced and the slide moved lengthwise from the groove. 85

Having thus described my invention, what I claim as new and desire to secure by Letters Patent is:—

1. An escutcheon comprising a plate having a key opening therethrough and an intersecting dovetailed groove extending across the plate, a slide mounted in the groove and formed with a threaded opening intermediate its ends, and a locking screw threaded in the slide opening and having a knurled outer 90 end and a tapered smooth inner end for movement into the path of the bolt-throwing part of a key.

2. An escutcheon comprising a plate having a key opening therethrough and an intersecting dovetailed groove, a slide mounted in the groove and formed with an aperture intermediate its length, and a locking screw threaded through the slide aperture and formed on its inner end with a smooth tapered point.

3. An escutcheon comprising a plate having a key opening therethrough and an inter-

secting groove, a slide mounted in the groove, and a locking screw threaded through the slide and passed through the plate opening for engagement with the bolt-throwing part 5 of a key.

4. An escutcheon comprising a plate having a key opening, a support secured across the opening, and a screw threaded through said support and extending through the key

opening of the plate for engagement with a 10 key.

In testimony whereof I have signed my name to this specification in the presence of two subscribing witnesses.

PERCY R. MOFFITT.
